UNITED STATES PATENT OFFICE.

FRANCIS H. BLATCH, OF HAZLETON, AND HARRY L. MCLEAN AND WILLIAM C. MENZIES, OF SCRANTON, PENNSYLVANIA; SAID BLATCH AND MCLEAN ASSIGNEES TO WILMOT ENGINEERING COMPANY, OF HAZLETON, PENNSYLVANIA, A CORPORATION OF PENNSYLVANIA.

COAL-WASHING APPARATUS.

Application filed December 6, 1927. Serial No. 238,012.

Our invention relates to coal washing apparatus wherein, preferably, the water for effecting the washing of the coal and the separation of slate, "bony" material, stone and the like therefrom is supplied continuously under the pressure requisite to effect such washing and separation.

It is a general object of the invention to provide an apparatus of the character described comprising means of novel construction whereby a device located in the path of the discharge of the mixture of coal, slate, "bony" material, stone and the like into the washing tank and a device located in the path of discharge of slate, etc., separated from the coal co-operate with each other to regulate and control the feeding of said mixture into the washing tank and the discharge of the slate, etc., therefrom.

It also is an object of the invention to provide the devices for controlling the feed of the mixture of coal, slate, "bony" material and the like into the washing tank and for controlling the discharge of the said slate, "bony" material and the like from the said tank with means or devices whereby clogging of the slate, "bony" material and the like is prevented and whereby the said slate, "bony" material and the like are caused to move or flow forward and to be discharged from the said tank.

To these and other ends the invention comprehends the construction and arrangement of parts as hereinafter described in detail, illustrated in the drawings and pointed out particularly in the claims.

In order that the invention may be readily understood and its practical advantages fully appreciated reference should be had to the accompanying drawings in which we have illustrated various forms of structures embodying our invention and illustrative of the principle of its operation.

In the drawings:

Fig. 1 is a view in top plan of a portion of a coal washing apparatus provided with and embodying our invention;

Fig. 2 is a view in vertical longitudinal section of the apparatus shown in Fig. 1;

Fig. 2^a is a view in transverse section of the slate discharge gate of the apparatus shown in Fig. 2;

Fig. 3 is a view in vertical section of a

portion of a washing apparatus provided with a modified construction of means embodying our invention, the said view being taken in a plane extending longitudinally of the said apparatus;

Fig. 4 is a view similar to that shown in Fig. 3, but showing still another modified construction of means embodying the invention; and

Fig. 5 is a similar view of a fragmentary portion of the structure also showing a slight modification of the structure.

In the drawings we have shown a coal washing apparatus provided with a frame structure indicated as a whole by the reference numeral 1 for supporting a water holding tank designated as a whole by the reference numeral 2. This tank is divided into various compartments as is usual in apparatus of this character, one of the said compartments being that in which the washing and cleaning of the coal are effected, the said compartment being indicated at 3. The mixture of coal and impurities, including slate, "bony" material, stone and the like is discharged from a chute 4 into the upper left hand portion of the compartment 3. The coal and the impurities move or flow forwardly through the compartment 3 underneath the baffle plate 5 which is indicated as being adjustable as is generally the case. The coal as it moves or flows through the compartment 3 is subjected to the action of a stream of water which is supplied from a source of supply (not shown) through an inlet 6 across the end of which a perforated plate 7 extends which plate constitutes a portion of the bottom of the compartment 3.

It may be noted that the forward wall of the inlet 6 is curved as indicated at 6^a and that the walls of the said inlet at its discharge end are so directed and related to the perforated plate 7 that the water is discharged herefrom in a vertical direction corresponding to the direction of the perforations 8 through the said plate. Any slush or deposit which may gather in the lower side of the inlet 6 may be removed through the opening 6^b controlled by a valve 6^c. The perforations 8 through the plate 7 may extend as shown in a vertical direction transversely of the direction of the movement of the flow of the material through the com-

partment 3. The water in its flow upwardly through and out of the compartment 3 strikes or collides with the mixture of coal and impurities and the former being of less specific gravity or more buoyant than the latter, is caused to flow upwardly and is discharged over the upper edge of the breast plate 10 and is conveyed from the tank through the chutes or troughs 15 from which it is discharged in known manner. The water which flows over the breast plate 10 with the coal is drained from the latter through the perforated bottoms of the chutes or troughs, also in known manner.

15 The impurities, consisting of the materials and substances previously indicated, being heavier or of greater specific gravity than the coal, moves or flows along upon or adjoining the bottom of the compartment 3 and is discharged from the compartment 3 through an opening formed by a vertically adjustable gate 20 in co-operation with the opposing lower edge portion of the perforated plate 7.

20 The mixture of coal and impurities as it is delivered or discharged from the chute 4 strikes against a control gate 21 which is connected near its opposite ends to arms 22 which in turn are connected to and supported upon a shaft 23 pivotally supported at its opposite end in bearings 24. It will be seen that the plate 21 is pivotally supported. The shaft 23 is provided at its middle point with an upwardly projecting arm 25 to the upper end of which a link 26 is connected the opposite end of which is connected to the upper end of the upwardly projecting arm of a bell crank lever 27 pivoted at 28 to a stationary support carried upon the upper side of the frame 1 of the apparatus. A vertically disposed link 30 is connected at its upper end to the lower end of the other arm of the said bell crank lever and its lower end to the outer end of an arm 31 connected to a shaft 32 pivotally supported in bearings at its opposite ends and provided with bracket arms 33 to which a plate 34 is connected. The plate 34 constitutes a gate which extends across and tends to close the opening through which the impurities are adapted to be discharged from the compartment 3.

25 The plates or gates 21 and 34 being pivotally supported and being connected by the connecting means as above described it will be seen that they are inter-related and interact and co-operate to control the rate of feed of the mixture of coal and impurities to the compartment 3 and the rate of the discharge of impurities from said compartment. The plates 21 and 34 and the connections therebetween are shown in the drawings in the position they occupy when the apparatus is not in operation. It will be understood that when the mixture of coal

and impurities strikes against the plate 21 it is moved or partially rotated about the axis of the shaft 23 so as to permit the said mixture to pass underneath the lower edge thereof into and forwardly within the compartment 3. Such pivotal movement of the plate 21 operates through the connections previously described to effect a like swinging movement of the plate 34 to permit discharge of the impurities which may be separated from the coal through the opening underneath the adjustable plate 20. The impurities thus discharged are conveyed from the tank by means of the endless conveyor means shown at 35 which is of usual construction and operates in the usual known manner. Any slush which may collect in the lower end of the pocket within which the conveyor 35 is located may be removed through the valve controlled opening 36.

It may happen that the mixture of the coal and impurities and the impurities after separation from the coal will tend to clog in the compartment 3 and thereby prevent it from flowing or moving forward in the said compartment. To prevent such occurrence we have provided what may be described as agitating devices consisting of a plurality of curved fingers 40 connected at their upper ends to the inner side of the plate or gate 21 and extending forwardly therefrom into the compartment 3. The said fingers are located at intervals and rest upon the bottom of the compartment 3 and terminate at points in rear of or to the left of the opening underneath the adjustable plate 20 for the discharge of the impurities from the compartment 3. Co-operating with the fingers 40 to prevent clogging of the impurities within the discharge opening therefor the plate or gate 34 is provided with rearwardly projecting fingers 41 which extend into positions underneath or slightly in rear of the adjustable plate 20. The movements of the fingers 40 and 41 effected by the movements of the plates or gates 21 and 34 agitate the mixture of coal and impurities and the latter after separation from the coal in the compartment 3 sufficiently to prevent the clogging of the material within the said compartment.

In the previous description we have referred primarily to the structure as disclosed in Figs. 1 and 2 of the drawings which differs somewhat from the construction illustrated in the subsequent figures of the drawings, but the principle of operation is substantially if not identically the same.

We shall now proceed with a description of the construction as illustrated in Fig. 3 wherein the coal is discharged from a chute 4 into the compartment 3 of the tank 2. The compartment 3 is provided with an adjustable baffle plate 5 the lower edge of which is in co-operative relation to the un-

per side of a member 45 mounted upon the inner side of the rear wall of the said tank 2. The upper and lower surfaces of the member 45 are angularly related to each other as shown in Fig. 4. The coal after it has passed underneath the lower edge of the adjustable baffle plate 5 and from the upper side of the member 45 falls onto the perforated plate 46 which constitutes the bottom of the compartment 3. The water for washing the mixture of coal, slate, "bony" material and other like material is discharged from a suitable source of supply through an inlet 47 into a compartment of the tank underneath the perforated plate 46 and flows therefrom through the said perforations in said plate and upwardly through the compartment 3. In its flow through the compartment 3 it effects separation of the coal from the impurities as described in connection with the construction illustrated in Figs. 1 and 2 of the drawings. The coal after separation from the impurities of the mixture is carried upwardly and forwardly and is discharged over the upper edge of the breast plate 10 and is conveyed thence through chutes such as those designated 15 in Figs. 1 and 2 of the drawings. The impurities which are separated from the coal move or flow forwardly underneath the rear edge of the rearwardly projecting or extending plate 48 secured to the rear side of the adjustable plate 49 the lower edge of which terminates a short distance above the upper side of the forward or right hand end portion of the perforated plate 46. The presence of the rearwardly extending plate 48 which extends transversely of the apparatus prevents or tends to prevent the descent of portions of coal which may have been separated from the impurities of the mixture downwardly into position to again be commingled with the impurities from which they may have been previously separated. The slate and other impurities which may have been separated from the mixture are discharged from the lower front edge of the plate 46 and are conveyed from the tank by means of an endless conveyor 35 of the usual construction and operating in the usual known manner.

Any slush or deposit which may be collected in the portion of the tank underneath the perforated plate 46 may be removed through the opening 50 controlled by the valve 51.

When the mixture of coal and impurities is discharged from the chute 4, in the construction shown in Fig. 4, it contacts with the plate 21' which is secured to and supported upon arms 22' which are secured to and depend from a shaft 23' journaled at its opposite ends in bearings one of which is indicated at 24'. A lever 55 is rigidly connected at a point intermediate its ends

to the said shaft 23'. The rear end portion of the said lever is provided with an adjustable weight 56. The opposite end of the said lever is connected to the upper end of a vertical link 57 the lower end of which is connected to the outer front end of an arm 58 connected at its rear end to a shaft 60 having depending arms 61 secured thereto to which is secured a plate 62 constituting a gate co-operating with the front edge of the perforated plate 46. When the mixture of coal and impurities strikes against the plate 21' it causes forward pivotal movement thereof to effect similar movement of the shaft 23' to elevate the front end portion of the lever 55. The elevation of the latter through the link 57 lifts the arm 58 to rock the shaft 60 to cause corresponding forward rocking movement of the plate or gate 62. The extent of the rocking movement of the arm 58 and of the shaft 60 may be varied somewhat by adjusting the connection between the upper end of the link 57 and the outer front end portion of the lever 55 toward and from the shaft 23'.

A slush valve is provided at 63 for the removal of slush or deposit from the pocket 66 within which the lower end portion of the conveyor 35 is located.

In the construction as illustrated in Fig. 4 of the drawings the parts designated by the reference numbers 2, 3, 5, 10, 35, 45, 46, 47, 48, 49, 50 and 51 are substantially identical with the parts correspondingly numbered in Fig. 3.

In said Fig. 4 the chute 4' discharges the mixture of coal and impurities to be washed into a short trough like member 70 the rear ends of the opposite sides of which overlie the opposite sides of the front end of the chute 4' and are pivoted thereto by means of pivots one of which is shown at 71. The forward end of one of the sides is pivotally connected with the lower end of a link 72 which is pivotally connected at its upper end to the rear end of a lever 73 pivoted intermediate its end to the upper end of a post or standard 74 supported upon a cross bar 75 mounted upon the upper side of the frame of the apparatus. The forwardly extending portion of the lever 73 is provided with a weight 76 which may be adjusted back and forth thereon. The forward portion of the said lever preferably at a point intermediate the weight 76 and the pivotal support for the said lever 73 is connected pivotally to the upper end of a link 77 which extends downwardly through a tubular projecting guide 78 and is connected at its lower end to the forward side of a plate or gate 79 which co-operates with the lower front edge of the perforated plate 46 to control or aid in controlling the discharge of the impurities, consisting of slate, "bony" material, stone and the like. The plate or gate 79 is

pivots connected at its upper edge by means of a pivotal connection indicated at 80 to the front side of the lower edge portion of the breast plate 10. When the apparatus 5 is not in use the parts 70 and 79 and the connections between the same occupy substantially the positions shown in Fig. 4, but when the mixture of coal and impurities is discharged into the short trough section 70 10 the weight thereof causes downward swinging movement of said trough to discharge the mixture therefrom which movement also causes pivotal movement of the lever 73 to swing the front end portion thereof bearing 15 the weight 76 upwardly which results in the elevation of the plate or gate 79. The said plate or gate 79 is of curved shape in cross section as shown. In consequence of such curved shape the relatively heavier impurities which may be banked against the inner or rear side thereof operate more effectively to aid in the opening of the said gate to permit the discharge of the said impurities.

The construction as illustrated in Fig. 5 25 of the drawings is identical with that shown in Fig. 4 except that the device or means 82 which is connected to the lower end of the link 77 is of different shape from the device 79. The device 82 is of substantially right 30 angular shape in cross section, one flange portion of which extends forwardly and occupies a substantially horizontal position and is pivoted by means of a pivot at 83 to a transverse partition or wall 84 extending 35 transversely of the tank and located a distance in advance of the point of discharge of the coal and impurities from the washing compartment 3. The other flange of the device 82 at the rear edge thereof extends 40 downwardly in a substantially vertical plane as indicated at 85 and its lower edge is adapted to rest upon the upper side of the lower front edge portion of the plate 46. The impurities which may be separated 45 from the coal contact with and may bank up against the rear side of the downwardly extending portion 85. The operation of the mechanism shown in Fig. 5 is substantially identical with the operation of the corresponding mechanism shown in Fig. 4 and, 50 for that matter, the corresponding mechanism shown in previous figures of the drawings.

It will be seen that by our invention we 55 have provided means at the point of delivery of the mixture of coal and impurities which is adapted to co-operate with means located at the point of discharge of the impurities from the washing compartment or 60 chamber after separation thereof from the coal and to control automatically the rate of delivery of the mixture to the washing compartment and also to control the discharge of the impurities from the said compartment. In other words the means lo-

cated at the points stated are connected and inter-related so as to co-operate in the manner and for the purpose hereinbefore indicated.

Having thus described our invention what 70 we claim and desire to secure by Letters Patent is:

1. In apparatus for washing coal, the combination of a tank having a compartment in which the coal is washed and separated from 75 its impurities, means adapted to be actuated by the discharge of the mixture of coal and impurities into the said compartment, movable means extending across the opening leading from said compartment through 80 which the impurities are discharged, means connected to said first named means and extending into said compartment for agitating the mixture of coal and impurities contained in said compartment upon movement of said 85 movable means, and connections between the said two means whereby the said means co-operate to control the delivery of the mixture of coal and impurities into the compartment and to control the discharge of impuri- 90 ties therefrom.

2. In apparatus for washing coal, the combination of a tank having a compartment within which coal is washed and separated 95 from its impurities, pivotally supported means extending across the path of discharge of the mixture of coal and impurities into the said compartment, pivotally supported means extending across an opening leading from said compartment through 100 which the impurities, after separation from the coal, are discharged, connections between the said two means whereby they react one upon the other and thereby control the delivery of the mixture of coal and impurities 105 into the said compartment and the discharge of the impurities therefrom, and means connected to each of said pivotally supported means and extending into said compartment for agitating the coal and impurities contained therein upon movement of said pivotally supported means.

3. In apparatus for washing coal, the combination of a tank having a compartment in which coal is washed and separated from its 115 impurities a portion of the said compartment being provided with a perforated bottom, means providing an inlet for discharging water through the said bottom, the said means being shaped to direct the flow of said water 120 in a direction parallel with the direction of the perforations through the perforated portion of the bottom of said compartment, a pivoted gate extending across the line of discharge of the mixture of coal and impurities 125 into the said compartment, means for pivotally supporting said gate, a gate extending across an opening in the front side of the said compartment through which the impurities, separated from the coal, are discharged, 130

means for pivotally supporting said last mentioned gate, connections between said gates whereby they co-operate with each other in controlling the discharge of the mixture of coal and impurities into the said compartment and in the discharge of the separated impurities therefrom, and a plurality of curved fingers connected to said first named gate and extending into engagement with the bottom of said compartment for agitating the coal and impurities contained therein upon movement of said gate.

4. In apparatus for washing coal, the combination of a tank having a compartment in which the coal is washed and separated from such impurities as may be intermingled therewith, said compartment having an opening through which the impurities which may be separated from the coal are discharged, a perforated plate extending across the lower end of said compartment, means for discharging a stream of water through the said perforated plate and through the said compartment to effect washing of the coal and the separation thereof from its impurities, movable means with which the mixture of coal and impurities contacts in its

passage to the said compartment, a pivotally supported gate located outside of said compartment and extending across the opening 30 leading therefrom through which the impurities are discharged, a connection between the said gate and the said movable means whereby movement of one causes movement of the other to thereby effect control of the 35 delivery of the mixture of coal and impurities into the said compartment and of the discharge of impurities from the said compartment after their separation from the coal, and fingers connected to said movable 40 means and to said gate for agitating the coal and impurities contained in said compartment upon movement of said movable means and of said gate.

In testimony whereof the said FRANCIS 45 H. BLATCH has hereunto signed his name this 17th day of October, 1927, and the said HARRY L. McLEAN and WILLIAM C. MENZIES have hereunto signed their names this 25th day of November, 1927. 50

FRANCIS H. BLATCH.
